cago, Ill., a corporation of Illinois

Application November 25, 1938, Serial No. 242,380

6 Claims. (Cl. 181—47)

This invention relates to both silencing and exhausting gases flowing from an internal combustion engine. Constructions for this purpose are commonly called "mufflers", and, while principally employed for automotive use, have wide application in connection with internal combustion engines generally and other situations where an explosive exhaust gas must be silenced and dissipated.

0 Muffler constructions now available for the purpose satisfactorily suppress the noises incident to vibrations carried by a pulsating current of gas, but present the objection that the travel of the gas through the muffler is not sufficiently rapid 5 and free as to insure against the building up of an appreciable back pressure. It is recognized by engineers that such back pressures interfere with the efficiency of operation of an internal combustion engine.

0 The employment of Venturi devices or tapered 10 nozzle means in mufflers some of which include the use of a cooling principle has been proposed, and while somewhat more efficient than other types of mufflers, do not overcome the problem 5 of reducing the back pressures to a minimum because they rely upon or permit the gas stream to undergo objectionable expansion during travel through the muffler. The present invention is an improvement over mufflers of this type and 0 enables the article to be made simply and inexpensively while, at the same time, possessing the desired silencing qualities and freedom from back pressure.

I have discovered that by providing a muffler 5 in which the exhaust gases are first allowed to expand in the muffler and are then immediately sub-divided and maintained in a plurality of streams, one of relatively high velocity and low pressure and the other of relatively low velocity 0 and high pressure and the pressure at all times is positively held substantially below the pressure of the initially expanded gas, that the gases flow rapidly and smoothly through the muffler whereby the muffler has the desired silencing 5 function and back pressure is rendered negligible. That is to say, the initially expanded gases are formed into and maintained in a plurality of streams by appropriate means comprising perforate members and associated elongated tapered 0 nozzles or Venturi devices. The nozzles are disposed in alignment and it is critical that their adjacent ends be spaced such a distance as (1) will prevent any substantial expansion or interference with the positive flow of the high velocity 5 stream, but (2) will allow the low velocity stream

to expand and be entrained due to the positive aspirating effect created by the high velocity stream. The incidental expansion of the high velocity stream as it traverses the enlarged ends of the respective nozzles is found to be negligible 5 in affecting the aforesaid results, and the gases travel through the muffler with a smoothness which permits a higher rate of speed than has heretofore been obtained.

The accompanying drawing illustrates a pre- 10 ferred embodiment of the invention, and it is to be understood that the muffler may vary as to its details without departing from the spirit of the invention.

Referring to the drawing,

Figure 1 is a longitudinal view partly in sec- 15 tion;

Figure 2 is a section on the line 2—2 of Fig- 20 ure 1;

Figure 3 is a section on the line 3—3 of Fig- 25 ure 1; and

Figure 4 is a sectional view of another embodiment of the invention.

Referring to Figure 1, the muffler includes the usual preferably cylindrical hollow body 10 which 25 may be of conventional shape and will be of a length suitable for the particular engine with which it is associated. In this connection, it is an important feature of the present invention that a muffler of substantially less length than 30 those usually required may be employed by reason of the improvements to be now described.

The body 10 is closed at its ends by suitable 35 caps 11 to which are connected the inlet 12 from the engine and the outlet 12' to the atmosphere. These caps may be suitably welded to the inner wall of the body 10 by welding as shown at 13.

The muffler is provided interiorly with a plu- 40 rality of stream dividing and maintaining means indicated as a whole at 14. As many of these means may be employed as required, and each of such means includes a perforate member 15 and a tapered nozzle or Venturi device 16. The perforate members 15, while preferably in the form of discs each having a multiplicity of circularly arranged openings 17 therein as shown 45 in Figure 2, may be in the form of spiders for supporting the tapered nozzles substantially centrally of the hollow body 10 and in alignment with each other. Each disc 15 has an outwardly turned flange 18 preferably welded to the inner wall of the body and a central opening 19 pro- 50 vided with a flanged wall 20 to which the Ven- turi device is suitably connected as by welding and supported in the required position. The 55

Venturi member 16 is preferably, although not necessarily provided with a plurality of openings 21 formed by striking the metal thereof inwardly to produce a plurality of vanes 22 as shown in Figures 1 and 3.

Referring to Figure 1, it is to be observed that the disc 15 adjacent the inlet side of the muffler is spaced from the cap a distance sufficient to produce an expansion chamber 23 in which the gases discharged from the engine instantaneously and continuously expand. This expansion of gases within the chamber 23 produces a condition of optimum muffler pressure which must be immediately dissipated. The term "optimum pressure" is used to describe the condition in the expansion chamber 23. That is, as the gas expands into this chamber, the optimum pressure created is materially lower than that existing in the muffler inlet pipe and the gas flow through the muffler being immediately established, this pressure is not only rapidly dissipated, but is never exceeded throughout the muffler. In other words, the highest pressure in the muffler is in the expansion chamber, and this, as explained, is appreciably lower than the pressure in the inlet pipe. In accordance with the present invention, I accomplish this result by causing a rapid and positive distribution of the pressure, i. e., dividing of the gas into separate streams A and B. The stream A will pass through the adjacent tapered nozzle or Venturi device and the other stream B will pass through the openings 17 and into the passage 24 defined between the outer wall of the nozzle and the wall of the body. It will be noted that the stream A passing through the Venturi member will have a progressively increasing velocity and progressively decreasing pressure, while the stream B surrounding the nozzle will have a progressively increasing pressure and a progressively decreasing velocity by reason of the increase in volume of the flow passage surrounding the nozzle. It is, moreover, to be noted that the path of stream B is circuitous while the path of stream A is direct and uninterrupted. Where the vanes 22 are employed, they do not obstruct to any appreciable extent the velocity of flow through the Venturi nozzle, but in some cases have been found desirable while in other cases are not required. The forming and maintaining of substantially separate streams A and B continues throughout the muffler by reason of the presence of a suitable number of the stream forming and maintaining means, and it is to be noted that the streams are substantially concentric and simultaneously flow in the same direction.

The position or proximity of the discs and associated Venturi devices with relation to each other is a critical factor in insuring that the initial pressure created in the expansion chamber 23 will be rapidly and smoothly dissipated. To this end, and regardless of the engine involved, the size of the muffler, the size of the stream forming and maintaining means and the openings therein, I have discovered that no opportunity must be afforded for any substantial expansion of the gases of stream A which would result in an objectional increase of pressure and a consequent decrease in velocity. In other words, this stream should travel continuously and positively at a high velocity and in an uninterrupted path through the muffler from end to end which result is attained by having the nozzles of a length to substantially bridge the space between consecutive perforate members. Fur-

thermore, I have discovered that it is essential that the gases of stream B be allowed to expand into stream A at a plurality of points of low pressure and be entrained therewith. Therefore, in assembling the muffler, the adjacent ends of the tapered nozzles should be so positioned as will produce these results. That is, the gases issuing from each Venturi nozzle should pass into the enlarged end of the next nozzle without substantially any of the gas of stream A expanding beyond the venturi and so that the low pressure condition of stream A will cause at least a portion of stream B at these spaced points to expand into stream A and be entrained therewith. This result is attained by causing the gases issuing from the small end of the Venturi nozzle to have such a high velocity that they will carry at least a portion of the gases from stream B with them into the entrance of the succeeding venturi, i. e., the high velocity stream will have an aspirating effect upon the gases in the surrounding low velocity stream. If the position of the Venturi members is so controlled, then the dissipation of pressure from the expansion chamber 23 is not only rapid, but of equal importance, smooth to the extent that back pressure becomes negligible and the muffler exerts the desired silencing function. Stated another way, after the creation of an optimum muffler pressure in the chamber 23, it is essential that the gas stream A which traverses a path through the nozzles is always at a high velocity, but at a pressure very substantially below that of the initial optimum expansion pressure.

While the velocity varies slightly as the stream A traverses the tapered Venturi devices, the average velocity is never below that which will produce the most efficient aspirating effect.

In another embodiment of the invention shown in Figure 4 the smaller ends 30 of the preceding nozzles extend into the larger ends 31 of the succeeding nozzles to obtain the desired aspirating effect. In this construction also it will be noted that the nozzle members are of a length to bridge the space between the perforate means.

I am aware that a certain amount of cooling and contraction of the gas takes place during travel through the muffler, but according to my observation, this result is insufficient of itself to produce the desired elimination of back pressure and it is necessary that the gas be conveyed at high speed through the muffler in the manner above described if the desired silencing effect and reduction of back pressure is to be attained.

As explained above, in addition to eliminating objectionable back pressure, the device of the present invention exerts an improved muffling action. Apparently, the sound energy wave caused by the explosion of the gases will be conducted along the exhaust pipe 12 and issue into the inlet of the muffler. By analogy to the well known example of a stone cast into a pond to establish a system wave, a spherical wave front is immediately established by the sound energy wave as it issues from pipe 12. A portion of the sound energy will flow outwardly on this spherical front into the expansion chamber and through the longitudinal path provided both through and about the tapering nozzles.

The sound wave passing into the expansion chamber will be reflected from the walls, against which it impinges, at an angle so that the reflected energy will be more or less out of phase with the following wave crests, and being out of phase, will tend to neutralize such following

crests. The portion of the sound wave entering the nozzle passage will be partially reflected from the tapered wall of the nozzles to establish an out of phase relationship between the reflected crest and the crests flowing straight through, such that the energy of the sound wave is dissipated by the interaction of the reflected wave energy and the energy of the flow passing straight through the nozzles. A similar interaction appears to take place in the path defined between the muffler wall and the outer wall surfaces of the nozzles.

The establishment of this out of phase relationship between various portions of the sound wave is repeated at each of the gas stream forming and maintaining means, i. e. at the nozzle structures, so that before the sound wave has reached the outlet end of the muffler its energy has been completely dissipated by reflection upon itself.

I claim:

1. A muffler including a hollow body, said body having an inlet and an outlet at opposite ends, a plurality of stream forming and maintaining devices fixed in said muffler and each including a perforate member and a tapered nozzle with the nozzles disposed substantially in alignment and said perforate members extending transversely of the muffler body, one of said transverse perforate members forming with the wall of the body an expansion chamber, the perforate members and tapered nozzles dividing the gas introduced to said expansion chamber into a plurality of streams, one of which travels through said nozzles at a high velocity and has a low pressure and the other of which travels about said nozzles at a low velocity and has a high pressure, each tapered nozzle being of a length to substantially bridge the space between consecutive perforate members and there being openings between the reduced end of one tapered nozzle and the adjacent enlarged end of the succeeding tapered nozzle whereby the high velocity stream flowing through the nozzles will exert an aspirating effect upon the other stream.

2. A muffler including a hollow body, said body having an inlet and an outlet at opposite ends, a plurality of stream forming and maintaining devices fixed in said muffler and each including a perforate member and a tapered nozzle with the nozzles disposed substantially in alignment and said perforate members extending transversely of the muffler body, one of said transverse perforate members forming with the wall of the body an expansion chamber, the perforate members and tapered nozzles dividing the gas introduced to said expansion chamber into a plurality of streams, one of which travels through said nozzles at a high velocity and has a low pressure and the other of which travels about said nozzles at a low velocity and has a high pressure, each tapered nozzle being of a length to substantially bridge the space between consecutive perforate members with the reduced end of one nozzle extending within the enlarged end of the succeeding nozzle and there being openings between said reduced and enlarged ends of said tapered nozzles whereby the high velocity stream flowing through the nozzles will exert an aspirating effect upon the other stream.

3. A muffler including a hollow body, said body having an inlet and an outlet at opposite ends, a plurality of stream forming and maintaining devices fixed in said muffler and each including a perforate disc member centrally supporting a

tapered nozzle with the nozzles disposed substantially in longitudinal alignment and said perforate members extending transversely of the muffler body, one of said transverse perforate members forming with the wall of the body an expansion chamber, the perforate members and tapered nozzles dividing the gas introduced to said expansion chamber into a plurality of streams, one of which travels through said nozzles at a high velocity and has a low pressure and the other of which travels about said nozzles at a low velocity and has a high pressure, each tapered nozzle being of a length to substantially bridge the space between consecutive perforate members and there being openings between the reduced end of one tapered nozzle and the adjacent enlarged end of the succeeding tapered nozzle whereby the high velocity stream flowing through the nozzles will exert an aspirating effect upon the other stream.

4. A muffler including a hollow body, said body having an inlet and an outlet at opposite ends, a plurality of stream forming and maintaining devices fixed in said muffler and each including a disc having a circular series of perforations, said disc centrally supporting a tapered nozzle with the nozzles disposed substantially in longitudinal alignment and said perforate members extending transversely of the muffler body, one of said transverse perforate members forming with the wall of the body an expansion chamber, the perforate members and tapered nozzles dividing the gas introduced to said expansion chamber into a plurality of streams, one of which travels through said nozzles at a high velocity and has a low pressure and the other of which travels about said nozzles at a low velocity and has a high pressure, each tapered nozzle being of a length to substantially bridge the space between consecutive perforate members and there being openings between the reduced end of one tapered nozzle and the adjacent enlarged end of the succeeding tapered nozzle whereby the high velocity stream flowing through the nozzles will exert an aspirating effect upon the other stream.

5. A muffler including a hollow body, said body having an inlet and an outlet at opposite ends, a plurality of stream forming and maintaining devices fixed in said muffler and each including a perforate member and a tapered nozzle with the nozzles disposed substantially in alignment and said perforate members extending transversely of the muffler body, each of said nozzles having a plurality of openings in the wall thereof, one of said transverse perforate members forming with the wall of the body an expansion chamber, the perforate members and tapered nozzles dividing the gas introduced to said expansion chamber into a plurality of streams, one of which travels through said nozzles at a high velocity and has a low pressure and the other of which travels about said nozzles at a low velocity and has a high pressure, each tapered nozzle being of a length to substantially bridge the space between consecutive perforate members and there being openings between the reduced end of one tapered nozzle and the adjacent enlarged end of the succeeding tapered nozzle whereby the high velocity stream flowing through the nozzles will exert an aspirating effect upon the other stream.

6. A muffler including a hollow body, said body having an inlet and an outlet at opposite ends, a plurality of stream forming and maintaining devices fixed in said muffler and each including a perforate member and a tapered nozzle with the

nozzles disposed substantially in alignment and said perforate members extending transversely of the muffler body, one of said transverse perforate members forming with the end wall of the body an expansion chamber directly communicating with the inlet, the perforate members and tapered nozzles dividing the gas introduced to said expansion chamber into a plurality of streams, one of which travels through said nozzles at a high velocity and has a low pressure and the other of which travels about said nozzles at

a low velocity and has a high pressure, each tapered nozzle being of a length to substantially bridge the space between consecutive perforate members and there being openings between the reduced end of one tapered nozzle and the adjacent enlarged end of the succeeding tapered nozzle whereby the high velocity stream flowing through the nozzles will exert an aspirating effect upon the other stream.
